W.P. McConnell.

Gas Making.

No 11740.

Patented Sept. 26. 1854.

UNITED STATES PATENT OFFICE.

WILLIAM P. McCONNELL, OF WASHINGTON, DISTRICT OF COLUMBIA.

IMPROVEMENT IN PROCESSES FOR MAKING ILLUMINATING-GAS FROM WOOD.

Specification forming part of Letters Patent No. **11,740**, dated September 26, 1854.

To all whom it may concern.

Be it known that I, WILLIAM P. McCONNELL, of Washington, in the District of Columbia, have invented a new and useful Improvement in Making Gas from Wood, of which the following is a full, clear, and exact description, reference being made to the accompanying drawing, which represents the heating and purifying apparatus in section.

The figure shows a sectional elevation of the apparatus.

Hitherto in the destructive distillation of wood for preparing charcoal or pyroligneous acid or gas for the purpose of illumination, it has been usual to condense the vapors immediately after leaving the retort, and in this way large amounts of tar and oils were run off. The gas obtained in such cases is always "poor," and burns with a blue flame, being deficient in carbon if the gas is washed and containing too much carbon if not washed, in the latter condition the carbon being in the form of smoke. I have discovered that by subjecting the gaseous and volatile products of the resinous woods to a high degree of heat after they leave the retort the gas may be procured for illumination of an excellent quality, giving a bright light, and at much less cost than gas from coal, rosin, or oil. The amount of tar is greatly diminished, nearly all being converted into gas, while the pyroligneous acid is more readily condensed and in a purer state than when driven off at a low temperature. There are various ways of subjecting the gases and vapors to a high degree of heat; but when it is done by the apparatus represented in the drawing there are particular advantages. I have found it advantageous to expand the gases into a large heater instead of passing them through contracted pipes, which latter would apply the heat more rapidly, but without the beneficial results of the former.

To effect the heating and purification of the gas I provide a receiver A, inclosed within a receiver B, making the flue-space between A and B about equal to the space B; or, in other words, the cross-section of the two chambers of equal area. The outer receiver B has a flange *g* at the top, upon which is bolted the cover *b*, and into this cover is inserted the escape-pipe *d*. The inner receiver is also

closed with a tight cover, into which is inserted the induction-pipe *C*; this pipe passing tightly through the cover *b* of receiver B. The outer receiver is provided with two lugs to sustain it when set on masonry. The under receiver *h* has an opening at the bottom, through which the gases pass into the outer receiver. Over this opening I place a grate *g'*, upon which I sometimes place brick or similar materials, through which the gas is to pass. The receivers are kept at proper distances by suitable projections *e e* attached to either receiver. The gas ascends between the receivers and out the exit-pipe, and may be taken thence directly to the gasometer, where the pyroligneous and empyreumatic products are readily absorbed and precipitated, the quantity being so small as not to require a separate washer. I may use an independent washer, but it is not necessary, the odor of the wood-gas being less offensive than from gases obtained from coal, rosin, or oil. It is not essential to specify any degree of heat to be used in this process; provided, only, that in the first stage of the process the heat be sufficient to effect the destructive distillation of wood, and that in the second stage of the process the gases and vapors be subjected to a degree of heat higher than that necessary to effect the decomposition of the wood, and this is the sense in which I use the expression "high degree of heat." It may be more or less, but usually in apparatus of small size the outer surface of the reheating-retort attains a low red heat. In larger works the temperature may be higher.

I will remark here that the usual process of operation with either coal, rosin, or oil will not answer in making gas from wood. Without the second heating the making of gas from wood suitable for common use is entirely impracticable.

I am aware that gas has been subjected to a high heat after leaving the retort when obtained from other materials, and in some cases with beneficial results; but I am not aware that it was ever contemplated to apply that process to wood-gas, and I am not aware that wood-gas has ever been introduced prior to my discovery. I have found wood-gas so made far more economical and agreeable and more brilliant than other gas, and having

been the first to make this important discovery I desire to secure it to myself, and to prevent others from using the same without my consent.

What I claim, therefore, as my invention and discovery is—

The improvement herein described in making gas from wood—viz., subjecting the pro-

ducts of destructive distillation therefrom to a high degree of heat, substantially in the manner and for the purposes herein set forth.

WM. P. McCONNELL.
